UNITED STATES PATENT OFFICE.

HOWARD E. SMART, OF OMAHA, NEBRASKA.

DESIGN FOR AN EMBLEM OR BADGE.

Application filed October 14, 1921. Serial No. 507,800. Term of patent 14 years.

To all whom it may concern:

Be it known that I, HOWARD E. SMART, a citizen of the United States, residing at Omaha, in the county of Douglas and State of Nebraska, have invented a new, original, and ornamental Design for an Emblem or Badge, of which the following is a specification, reference being had to the accompanying drawing, forming part thereof.

The figure is a plan view of an emblem or badge constituting my design.

I claim:

The ornamental design for an emblem or badge as shown.

HOWARD E. SMART.
